Application March 10, 1948, Serial No. 13,992

9 Claims. (Cl. 89—33)

1

This invention relates to ammunition boosters adapted to assist in feeding ammunition to a machine gun mounted upon an airplane or other armed vehicle.

It has been proposed heretofore to provide a motor driven sprocket for acting upon the ammunition carried by a loaded ammunition belt to assist in feeding the belt with its ammunition to a machine gun. In accordance with the prior proposal the motor was to be arranged to operate constantly so long as the firing circuit was closed and was to be connected to drive the booster sprocket continuously, so long as the motor continued in operation.

A booster designed for operation upon this principle has to be adjusted to the speed of operation of the particular gun, and even then is apt to get out of order, because when the belt is long and heavy the load is apt to be too great, and when the belt is short and light the delivery force of the ammunition to the gun and the rate of booster feed are likely to be too great.

The present invention has for its primary object to provide an ammunition booster comprising a motor and a sprocket driven by the motor, in which there is no need to adjust the booster operation to the firing rate of the gun and in which the force and rate of delivery of the ammunition to the gun are, without preliminary adjustment, automatically maintained within safe and proper limits.

To these ends it is a salient feature of the present invention that the booster is operated from a drive motor through a clutch, and that the ammunition belt is carried forward from the booster sprocket to the gun over a belt engaging control member for the clutch. When the belt between the booster and the gun is sufficiently slack, it rests upon the control member and causes the clutch to be disengaged, thereby breaking the connection between the motor and the sprocket. As the normal gun feed mechanism continues to act upon the ammunition carried by the belt, the slack between the booster and the gun is reduced. This reduces the weight upon the control member and causes the clutch to be reengaged, thereby reestablishing the drive of the sprocket by the motor. The booster sprocket, when in operation, advances the belt more rapidly than the belt is advanced by the feeding mechanism of the gun, so that the amount of slack is increased by the sprocket, and the clutch is again disabled. The booster is thus intermittently actuated by the continuously running motor to advance the ammunition, at the

2

same average rate at which the ammunition is advanced by the gun itself.

With this kind of arrangement the booster can never overfeed. At the same time it can be designed to provide sufficient power to operate successfully under all normal conditions. The load imposed upon the normal ammunition feeding mechanism of the gun is automatically held within strict limits.

It is desirable when loading the gun to be able to advance the ammunition booster by manual operation, but at the same time to prevent retrograde movement of the booster. To this end the drive is transmitted from the clutch to a drive shaft upon which a brake is operative, and the brake is made responsive to the clutch control member so that the brake and clutch are alternatively effective. A one-way ratchet clutch is desirably provided between the drive shaft and the booster sprocket, the clutch being designed to drive the sprocket forward and to permit forward operation of the sprocket relative to the drive shaft when the drive shaft is idle, but not the reverse operation of the sprocket relative to the idle drive shaft.

It is an object of the present invention to adapt the booster for right-hand or left-hand installation and for endwise reversal. With these objects in view the booster motor is constructed and arranged so that it may be conveniently installed for rotation in either one direction or the other. Instead of providing a single one-way clutch between the drive shaft and the sprocket, two such clutches are provided, the one for effecting the drive when the motor is operated in one direction and the other for effecting the drive when the motor is operated in the opposite direction.

The clutches, which are desirably toothed clutches, are individually manually adjustable to effective and ineffective positions, but normally the adjusting means for one or the other of the clutches is disabled so as to assure the retention of that clutch in an inoperative condition. The clutch which is permitted to remain operative is selected in accordance with the direction of motor operation, so as to permit manual operation of the sprocket in the direction to advance the ammunition toward the gun while preventing retrograde movement of the sprocket. When it is desired to operate the sprocket backward, however, the effective toothed clutch can be temporarily shifted to inactive position.

As has been indicated, it is also an object of the invention to enable the booster to be re-

versed end for end so as to improve the adaptability of the device for varying installations. The booster sprocket comprises a rotatable sleeve having a pair of sprocket gears mounted upon it. One of the sprocket gears has the gaps between its teeth formed to engage and coact with the ammunition shells, and the other has the gaps between the teeth of smaller radius to coact with the projectiles. The two sprocket gears, however, have equal numbers of teeth and are of the same internal diameter, being adapted to be interchangeably mounted upon the sprocket cylinder.

Other objects and advantages will hereinafter appear.

In the drawing forming part of this specification:

Fig. 1 is a fragmentary view in sectional elevation of a booster sprocket which forms part of a practical and advantageous illustrative form of booster mechanism embodying features of the invention;

Fig. 2 is a fragmentary sectional view in elevation of the booster mechanism of Fig. 1 as seen from the left-hand end of that figure;

Fig. 3 is a fragmentary sectional view taken upon the line 3—3 of Fig. 1 looking in the direction of the arrows;

Fig. 4 is a fragmentary sectional view taken upon the line 4—4 of Fig. 1 looking in the direction of the arrows;

Fig. 5 is a fragmentary view in end elevation of the booster mechanism shown in Fig. 1 as seen from the right-hand end of that figure;

Fig. 6 is a fragmentary sectional view taken upon the line 6—6 of Fig. 4 looking in the direction of the arrows;

Fig. 7 is a fragmentary sectional view taken upon the line 7—7 of Fig. 4 looking in the direction of the arrows;

Fig. 8 is a view in rear elevation of a machine gun having the ammunition booster and ammunition chute of the present invention combined therewith; and

Fig. 9 is a diagrammatic view illustrating the circuits of the booster motor and the magnetic clutch.

Reference will first be had to Fig. 8. In this view disclosure is made of a machine gun and gun mount indicated generally by 1, an ammunition booster 2, and an ammunition chute 3 disposed between the booster and the gun through which the ammunition belt 4, which includes the ammunition itself, is advanced from the booster to the gun. It is to be understood, of course, that the machine gun itself includes the usual ammunition feeding mechanism, and that the booster is provided in installations where the weight and length of the ammunition belt make auxiliary feeding means desirable.

The booster 2, Fig. 1, comprises a rotatable sprocket sleeve 5 having external bosses or collars 6 and 7 provided upon it for seating sprockets 8 and 9, respectively. Series of ears 10 and 11 are provided in association with the collars 6 and 7 for attaching the sprocket gears 8 and 9 in place. The attachment is effected through screws 12 which are passed through the ears and clamped in place by nuts 13. The sprockets 8 and 9 are adapted to coact, respectively, with the shells and projectiles of cartridges. The sprockets are interchangeably mounted upon the flanges 6 and 7 so that the booster can be pointed in either direction relative to the gun as desired. The sleeve 5 is rotatably mounted through ball bear-

ings 14 and 15 upon stationary end plates 16 and 17. Threaded bores 18 and 19 are provided in the external faces of the plates 16 and 17 for the reception of mounting screws.

The plate 16 is connected through screws 20 to a motor housing end plate 21 which is disposed interiorly of the sleeve 5, insulating plates 22 and 23 being interposed between the blocks 16 and 21. One end of the armature shaft 24 is supported in a ball bearing 25 carried by the plate 21. The plate 21 is secured to a motor casing 26 by means of screws 27. An insulating ring 28 is secured in the sleeve 26 by means of screws 29. Metallic sleeves 30 carried by the ring 28 constitute holders or guideways for commutator brushes 31 which are urged by springs 32 toward the commutator of the motor armature 33.

The armature shaft 24 is supported at its opposite end in a ball bearing 41 which is carried by a stationary plate 42, the plate being secured in the stationary sleeve 26 by screws 43. The plate 42 is composed of a highly permeable ferromagnetic material for a purpose which will be hereinafter explained.

A further stationary plate 44 is fitted within the right-hand end of the sleeve 26 and carries a ball bearing 45 in which a drive shaft 46 is mounted. The plate 44 is secured by screws 47 to a stationary block 48. The block 48 is connected by screws 49 with the end plate 17.

The sleeve 26 has secured to it by screws 50 an inner sleeve 51. The inner sleeve 51 in turn is secured by screws 52 to a frame structure 53 by which motor field windings 54 and 55 are carried.

The motor armature shaft 24 has affixed to the right-hand end thereof a driving disc 56 which is adapted through the medium of a friction disc clutch 57 to transmit rotation to a drive shaft 46 through which the sprocket sleeve 5 is driven. The clutch 57 is located within a core member 58 upon which an electromagnet winding 59 is carried. Alternate discs of the clutch 57 are splined to a sleeve 60 which is affixed to the driving disc 56. The other alternate discs of the clutch are splined to a sleeve member 61 which is, in turn, splined to the drive shaft 46.

A compression coil spring 62 is interposed between a nut 63, threaded on the drive shaft, and a radial wall of the sleeve 61. The spring urges the sleeve 61 away from the drive disc 56 when the electromagnet is not energized, thereby rendering the clutch 57 ineffective. When the electromagnet is energized, however, the core 58 is drawn to the left toward the fixed plate 42 and acts to move with it by means of a bearing 61a the sleeve 61, so that the discs of the clutch 57 are pressed toward the drive disc 56 and are clamped firmly in engagement with one another to drive the shaft 46 from the disc 56.

When the electromagnet is de-energized the core 58 is forced toward the right by the spring 62 and causes the discs of another clutch 64 to be pressed firmly together. The clutch 64 comprises a pair of discs splined to the shaft 46 and an intervening disc splined to the non-rotary core member 58. When this last mentioned clutch is rendered effective therefore by the rearward movement of the core 58, it serves as a brake for arresting rotation of the drive shaft 46 and holding the drive shaft against unintended rotation. The core member 58 is guided in its axial movements and is held against rotation by guide pins 65 (one shown) which are affixed to the core member and slidably received in bores 66 formed in the stationary plate 44.

Alternative clutch and gear trains are provided for transmitting motion from the drive shaft 46 to the sprocket sleeve 5. These clutch and gear trains are intended to be employed alternatively according to the direction in which the motor armature is rotated. The two trains are illustrated respectively in Figures 6 and 7 and are duplicates of one another, save for a single detail which will be specifically pointed out at an appropriate point.

The drive shaft 46 carries a pinion 67 which meshes with and drives a gear 671 fast upon an intermediate shaft 672. The shaft 672 has formed upon it a pinion 673 which meshes with and drives the input gears 68 and 68a of the two trains. Since the two trains are so nearly duplicates of one another, the train embodying the gear 68 will be described, and no specific description will be given the train embodying gear 68a. Corresponding reference numerals will, however, be applied to corresponding parts of the latter train with the subscript "a" added in each instance.

The gear 68 is revoluble upon a shaft 69 and bears against a split ring 691 which is sprung into a circumferential groove 692 of the shaft. The shaft 69 is supported at its left-hand end in a ball bearing 70 carried by the plate 44, and at its right-hand end in a roller bearing 701 carried by the plate 17. The gear 68 is formed with a circular flange portion 71 which is internally splined to a disc 72. The disc 72 is slidably mounted upon the shaft 69 and is urged away from the body of the gear 68 by a compression coil spring 73 which is interposed between the disc and the gear body. The disc 72 has a toothed hub portion 74, the teeth of which are adapted to interfit with complementary teeth 75 formed on a hub portion of a gear 76, the gear 76 being fast upon the shaft 69. It will be apparent that the toothed hubs of the disc 72 and the gear 76 form a toothed clutch adapted to transmit drive from the gear 68 to the gear 76 for one direction of rotation of the gear 68 but not for the opposite direction of rotation of the gear.

The train comprising the gear 68 is designed to be used only when the direction of motor drive is such that the top teeth of the gear 68 travel toward the observer as the parts are viewed in Fig. 6. The train comprising the gear 68a is intended to be used only when the motor drive is in the opposite direction, that is to say when the teeth at the top of 68a travel away from the observer as the parts are viewed in Fig. 7. As the parts are observed in Fig. 4, the train comprising gear 68 is utilized for transmitting clockwise rotation to the sprocket sleeve 5 and the train comprising gear 68a is utilized for transmitting counter-clockwise rotation to the sprocket sleeve 5. The gears 76 and 76a mesh with an internal gear 81 which is secured to the sprocket sleeve 5 by screws 82.

The disc 72 is engaged by a clutch shifting fork 83 which is pivotally mounted upon a pin 84 and which is urged toward the right by the spring 73 acting through the disc 72. A fork operating rod 85 is slidably mounted in the plate 17 and is provided with an operating handle 86 disposed at the outer or right-hand side of the plate 17. The rod 85 is provided with a cross pin 87 which is adapted to rest in a shallow recess 88 of the plate 17 when holding the fork 83 in clutch disengaging position against the force of spring 73.

In order to permit the fork to move rearward and enable the clutch members to become engaged with one another, the rod 85 is first thrust

forward to move the pin 87 clear of the notch 88 and is then turned through a right angle to align the pin 87 with a deeper notch 89. The deeper notch 89 is not shown in Fig. 6, but the corresponding notch of the duplicate mechanism of Fig. 7 is shown at 89a. The pin 87a is shown as resting in the notch 89a in Fig. 7, so that the clutch parts are illustrated in that figure in engaged or driving relation.

While it would do no harm for both toothed clutches to be engaged simultaneously, there is no utility in having them engaged simultaneously and such simultaneous engagement would result in unnecessary noise and unnecessary wear of the parts. Provision is accordingly made of an interlock device at the outer side of the plate 17 which may be adjusted to permit either of the handles 86 and 86a to be operated between the clutch engaging and clutch releasing positions, but which will never permit both of the handles to be operated simultaneously to clutch engaging positions.

The interlock device comprises a slotted arm 91 (Fig. 5) through which a headed screw 92 is passed. The arm 91 rests upon a pair of spaced ears 93, and the screw extends down between the ears. A clamping nut 94 is threaded on the screw and may be tightened against the under side of the ears 93 to clamp the bar 91 against the upper side of the ears. The bar may be adjusted to a position like that shown in Fig. 5 in which the handle 86 is operable between clutching and declutching positions but the handle 86a is compelled to remain in its declutching position.

The position of the interlock bar 91 can be changed by first operating the handle 86 to declutching position, loosening the nut 94, sliding the bar 91 across to lie beneath the handle 86 but to clear the handle 86a, and again tightening the nut.

The electromagnetic clutch coil 59 is made subject, during continuous running of the motor, to the control of a slack switch 97 which is arranged to be controlled by that portion of the ammunition belt which extends from the booster sprocket 2 over to the gun 1. This portion of the belt is caused to travel through an ammunition chute 3, the floor portion of which is desirably curved to coincide substantially with a catenary which would normally be formed by the freely suspended belt. The floor 98 of the chute 3 comprises, at the lowest portion thereof, a hinged section 99 which is free to move downward under the weight of the belt, but which is urged upward by a spring 100 which acts through a switch member 101.

When there is enough slack in the belt between the sprocket and the gun to cause the floor member 99 to push the switch member 101 down to a circuit breaking position, the magnet clutch coil 59 is deenergized, and causes the drive shaft to be disconnected from the drive disc 56 and to be arrested by the action of the braking clutch 66. The booster sprocket is accordingly brought to rest promptly whenever the switch member 101 is moved to circuit breaking position.

So long as the gun is firing, however, the ammunition feed mechanism of the gun itself continues to operate and to draw ammunition from the slack portion of the belt that has already passed the booster sprocket. This reduces the length of the slack belt between the sprocket and the gun, causing the belt to be lifted away from the movable floor section 99 of the ammunition chute, and hence enabling the switch member

101 to be returned to circuit closing position by the action of the spring 100.

As soon as the switch member 101 again closes the circuit of the clutch coil 59, the motor, which has continued to run, is again connected to drive the booster sprocket. The booster sprocket, when set into operation, always gains upon the ammunition feeding mechanism of the gun and hence the sprocket is caused automatically to be started and stopped at short intervals during the operation of the gun and motor as the switch member 101 is alternately opened and closed.

It has been mentioned that the gear and clutch trains comprising the gear 68 and 68a are alternatively utilized depending upon the direction of rotation of the motor armature 33. The electric connections to the motor and to the clutch coil 59 are shown in Fig. 9, which figure should be read in conjunction with the Fig. 3.

A line conductor 105 connected to the positive terminal of a direct current source is connected to a terminal block 106 which is mounted on but insulated from the motor housing plate 21. A line conductor 107 runs from the negative terminal of the same direct current source to a terminal block 108 which is mounted upon but insulated from the motor housing plate 21. Additional terminal blocks 109 and 110 are mounted upon but insulated from the motor housing plate 21.

A master switch (not shown) is desirably provided for the motor in one of the line conductors 105, 107. This switch may advantageously be arranged to be opened and closed, respectively, concurrently with the opening and the making ready of the gun firing circuit.

As will be seen from an examination of Fig. 9, the slack switch and magnet clutch circuit may be traced out from line conductor 105 through a conductor 111, switch 97, conductor 112, terminal block 110, conductor 113, winding 59, conductor 114, and terminal block 108 to line conductor 107.

The motor is of the compound type, having the field 54 disposed in shunt with the armature 33 and field 55 disposed in series with the armature 33. The circuit of the shunt field 54 may be traced from line conductor 105 through terminal block 106, conductor 115, field winding 54, conductor 116, and terminal block 108 to line conductor 107.

The circuit through the series winding 55 may be traced from line conductor 105 through terminal block 106, conductor 117, armature 33, conductor 118, terminal block 109, conductor 119, field winding 55, conductor 120, and terminal block 108 to line conductor 107. This is the full line circuit illustrated in Fig. 9.

If it is desired to change the direction of rotation of the motor armature, the direction of current flow through the armature is simply reversed. This is done by crossing conductors 117 and 118 as illustrated in dash lines in Fig. 9. The conductor 117 is disconnected from terminal block 106 and is connected as illustrated by dash line 117a to terminal block 109. Conductor 118 is at the same time disconnected from terminal block 109 and is connected as illustrated by dash line 118a to terminal block 106.

Now the circuit from line conductor 105 through the armature and the series connected field 55 is traced out through terminal block 106, conductor 113, as indicated by the portion 118a, armature 33, conductor 117, as indicated by the portion 117a, terminal block 109, conductor 119, field winding 55, conductor 120, and terminal block 75

108 to line conductor 107. The circuit is precisely the same as before with the exception that the direction of current flow through the armature has been reversed by the reversal of the connections of the conductors 117 and 118.

It is to be understood, of course, that the direction of motor rotation chosen for a particular installation is never altered. It is not therefore necessary, nor desirable, to make the provision for reversal of direction so readily accessible as to facilitate tampering by unskilled and unauthorized persons. In order, however, that reasonably easy access may be had to the terminal blocks provided upon the plate 21, the end plate 16 is formed with an opening 121 through it, and this opening is normally covered by a plate 122 which is removably secured to plate 16 by screws 123.

When the direction of motor rotation has been settled upon, as determined by the relation of the booster to the gun which is physically most convenient in a particular instance, the interlock bar 91 is set to disable the clutch controlled by the handle 86 or 86a which ought not be rendered effective for the direction of motor rotation which has been chosen. The sprockets 8 and 9 are then checked to make sure that they are mounted consistently with the orientation of the booster sleeve 5 with relation to the gun which has been chosen. If the sprockets 8 and 9 are not found to be properly disposed they are interchanged in the manner which has been already pointed out.

The handle 86 or 86a which is not disabled by the interlock bar 91 may be operated to disable the clutch controlled by it when desired, as, for example, if it should become necessary to feed the belt backward past the sprocket.

I have described what I believe to be the best embodiment of my invention. I do not wish, however, to be confined to the embodiment shown, but what I desire to cover by Letters Patent is set forth in the appended claims.

I claim:

1. An ammunition booster for advancing a loaded ammunition belt toward a machine gun having ammunition feeding instrumentalities, said booster comprising a feed sprocket, a constantly running drive motor, a drive shaft for the sprocket, a driving clutch interposed between the motor and the drive shaft, a brake associated with the drive shaft, a clutch operating member operable to render the clutch and the brake effective alternatively, an electromagnet controlling the clutch operating member, and a slack switch in circuit with the electromagnet comprising a belt engaging member, the construction and arrangement being such that the electromagnet circuit is opened to cause the brake to be effective when the belt slack between the sprocket and the gun exceeds a predetermined amount and to cause the clutch to be effective when the belt slack is reduced below such amount.

2. An ammunition booster for advancing a loaded ammunition belt toward a machine gun when set up in any one of a plurality of relations to the gun, said booster having ammunition feeding instrumentalities, and comprising a feed sprocket, a constantly running drive motor adapted for operation in one direction or the other according to the disposition of the booster in relation to the gun, a drive shaft for the sprocket, a drive clutch interposed between the motor and the drive shaft, a slack responsive clutch controlling member engageable with the ammunition belt between the sprocket and the gun for

causing the clutch to be rendered ineffective when the belt slack between the sprocket and the gun exceeds a predetermined amount and to be rendered effective when the belt slack is reduced below such amount, a pair of one-way clutch and gear trains interposed between the drive shaft and the sprocket and adapted to be used selectively according to the direction of drive shaft operation, the one for driving the sprocket in one direction from the drive shaft while permitting the sprocket to be turned manually in that direction relative to the drive shaft when the drive shaft is idle, and the other for driving the sprocket in the opposite direction from the drive shaft while permitting the sprocket to be turned manually in the latter direction relative to the drive shaft when the drive shaft is idle.

3. An ammunition booster for advancing a loaded ammunition belt toward a machine gun when set up in any one of a plurality of relations to the gun, said booster having ammunition feeding instrumentalities, and comprising a feed sprocket, a constantly running drive motor adapted for operation in one direction or the other according to the disposition of the booster in relation to the gun, a drive shaft for the sprocket, a drive clutch interposed between the motor and the drive shaft, a slack responsive clutch controlling member engageable with the ammunition belt between the sprocket and the gun for causing the clutch to be rendered ineffective when the belt slack between the sprocket and the gun exceeds a predetermined amount and to be rendered effective when the belt slack is reduced below such amount, a brake operative on the drive shaft and controlled by the slack responsive member to be ineffective when the clutch is effective and to be effective to prevent retrograde rotation of the drive shaft when the clutch is rendered ineffective, a pair of one-way clutch and gear trains interposed between the drive shaft and the sprocket adapted to be used selectively according to the direction of drive shaft operation, the one for driving the sprocket in one direction from the drive shaft while permitting the sprocket to be turned manually in that direction only relative to the drive shaft, when the drive shaft is idle, and the other for driving the sprocket in the opposite direction from the drive shaft while permitting the sprocket to be turned manually in the latter direction only relative to the drive shaft when the drive shaft is idle.

4. An ammunition booster for advancing a loaded ammunition belt toward a machine gun when set up in any one of a plurality of relations to the gun, said booster having ammunition feeding instrumentalities, and comprising a feed sprocket, a constantly running drive motor adapted for operation in one direction or the other according to the disposition of the booster in relation to the gun, a drive shaft for the sprocket, a drive clutch interposed between the motor and the drive shaft, a slack responsive clutch controlling member engageable with the ammunition belt between the sprocket and the gun for causing the clutch to be rendered ineffective when the belt slack between the sprocket and the gun exceeds a predetermined amount and to be rendered effective when the belt slack is reduced below such amount, a brake operative on the drive shaft and controlled by the slack responsive member to be ineffective when the clutch is effective and to be effective to prevent retrograde rotation of the drive shaft when the

clutch is rendered ineffective, a pair of one-way clutch and gear trains interposed between the drive shaft and the sprocket adapted to be used selectively according to the direction of drive shaft operation, the one for driving the sprocket in one direction from the drive shaft while permitting the sprocket to be turned manually in that direction only relative to the drive shaft, when the drive shaft is idle, and the other for driving the sprocket in the opposite direction from the drive shaft while permitting the sprocket to be turned manually in the latter direction only relative to the drive shaft when the drive shaft is idle, and manually operable controllers for the respective one-way clutches, each settable to render active or inactive the one-way clutch with which it is associated.

5. An ammunition booster for advancing a loaded ammunition belt toward a machine gun when set up in any one of a plurality of relations to the gun, said booster having ammunition feeding instrumentalities, and comprising a feed sprocket, a constantly running drive motor adapted for operation in one direction or the other according to the disposition of the booster in relation to the gun, a drive shaft for the sprocket, a drive clutch interposed between the motor and the drive shaft, a slack responsive clutch controlling member engageable with the ammunition belt between the sprocket and the gun for causing the clutch to be rendered ineffective when the belt slack between the sprocket and the gun exceeds a predetermined amount and to be rendered effective when the belt slack is reduced below such amount, a brake operative on the drive shaft and controlled by the slack responsive member to be ineffective when the clutch is effective and to be effective to prevent retrograde rotation of the drive shaft when the clutch is rendered ineffective, a pair of one-way clutch and gear trains interposed between the drive shaft and the sprocket adapted to be used selectively according to the direction of drive shaft operation, the one for driving the sprocket in one direction from the drive shaft while permitting the sprocket to be turned manually in that direction only relative to the drive shaft, when the drive shaft is idle, and the other for driving the sprocket in the opposite direction from the drive shaft while permitting the sprocket to be turned manually in the latter direction only relative to the drive shaft when the drive shaft is idle, manually operable controllers for the respective one-way clutches, each settable to render active or inactive the one-way clutch with which it is associated, and an interlock member so mounted with respect to the one-way clutch controllers that at all times at least one or the other of the controllers must remain in position to render its associated one-way clutch inactive, said interlock member being operable between two positions in one of which one of the one-way clutches is compelled to remain inactive while the other may be rendered active or inactive and in the other of which the other of the one-way clutches is compelled to remain inactive while the first may be rendered active or inactive.

6. An ammunition booster adapted for endwise reversal comprising, in combination, a drive motor, a sleeve containing the motor, said sleeve having a pair of sprocket gears fast upon it, the one constructed and arranged for cooperating with the ammunition shells and the other for cooperating with the projectiles which are of

smaller diameter than the shells, said sleeve being provided with identical mounting parts for the two gears, and the gears being formed for interchangeable mounting on the sleeve.

7. An ammunition booster adapted for advancing a loaded ammunition belt toward a machine gun when set up in any one of a plurality of relations to the gun, said booster having ammunition feeding instrumentalities, and comprising a feed sprocket, a constantly running drive motor adaptable for operation in one direction or the other according to the disposition of the booster in relation to the gun, a drive shaft for the sprocket, an electromagnetic clutch interposed between the motor and the drive shaft, a slack responsive clutch controlling switch engageable with the ammunition belt between the sprocket and the gun for causing the clutch to be rendered ineffective when the belt slack between the sprocket and the gun exceeds a predetermined amount and to be rendered effective when the belt slack is reduced below such amount, a brake operative on the drive shaft and controlled by the slack switch to be ineffective when the electromagnetic clutch is effective and to be effective when the electromagnetic clutch is ineffective, a pair of one-way clutch and gear trains interposed between the drive shaft and the sprocket, adapted to be used selectively according to the direction of drive shaft operation, the one for driving the sprocket in one direction from the drive shaft while permitting the sprocket to be turned manually in that direction only relative to the drive shaft when the drive shaft is idle, and the other for driving the sprocket in the opposite direction from the drive shaft while permitting the sprocket to be turned manually in the latter direction only relative to the drive shaft when the drive shaft is idle.

8. An ammunition booster for advancing a loaded ammunition belt toward a machine gun having ammunition feeding instrumentalities, said booster comprising a feed sprocket, a constantly running drive motor, a drive shaft for the sprocket, a clutch interposed between the motor and the sprocket, a brake operative on the drive shaft, a slack responsive clutch controlling member engageable with the ammunition belt between the sprocket and the gun for causing the drive to be interrupted when the belt slack between the sprocket and the gun exceeds a predetermined amount and to be reestablished when the belt slack is reduced below such amount, said slack responsive member serving also to render the drive shaft brake effective when the clutch is rendered ineffective, and to render said brake

ineffective when the clutch is rendered effective, and a one-way clutch and gear train between the drive shaft and the sprocket constructed and arranged to drive the sprocket from the drive shaft when the drive shaft is in operation and to permit the sprocket to be turned manually in the same direction relative to the drive shaft when the drive shaft is idle, said one-way clutch and gear train serving also to prevent retrograde movement of the sprocket relative to the drive shaft when the drive shaft is idle.

9. An ammunition booster for advancing a loaded ammunition belt toward a machine gun having ammunition feeding instrumentalities, said booster comprising a feed sprocket, a constantly running drive motor, a drive shaft for the sprocket, a clutch interposed between the motor and the sprocket, a brake operative on the drive shaft, a slack responsive clutch controlling member engageable with the ammunition belt between the sprocket and the gun for causing the drive shaft to be interrupted when the belt slack between the sprocket and the gun exceeds a predetermined amount and to be reestablished when the belt slack is reduced below such amount, said slack responsive member serving also to render the drive shaft brake effective when the clutch is rendered ineffective, and to render said brake ineffective when the clutch is rendered effective, and a one-way clutch and gear train between the drive shaft and the sprocket constructed and arranged to drive the sprocket from the drive shaft when the drive shaft is in operation and to permit the sprocket to be turned manually in the same direction relative to the drive shaft when the drive shaft is idle, said one-way clutch and gear train serving also to prevent retrograde movement of the sprocket relative to the drive shaft when the drive shaft is idle, and a controller through which the one-way clutch can be set in engaged or disengaged condition at will.
